UNITED STATES PATENT OFFICE.

HENRY H. KREIGER, OF BRADDOCK, PENNSYLVANIA.

CURTAIN STRETCHER.

Application filed February 15, 1922. Serial No. 536,737.

To all whom it may concern:

Be it known that I, HENRY H. KREIGER, a citizen of the United States, residing at Braddock, State of Pennsylvania, have invented new and useful Improvements in Curtain Stretchers, of which the following is a specification.

This invention relates to curtain stretchers, and more particularly to a curtain 10 stretcher having means for supporting the same in upright or standing position.

One of the main objects of the invention is to provide a curtain stretcher of the character stated of simple construction and 15 operation which may be readily produced at small cost. A further object is to provide a curtain stretcher which may be readily disassembled and, when disassembled, can be packed so as to occupy very 20 little space. Further objects will appear from the detailed description.

In the drawings:

Figure 1 is a front view of the stretcher set up;

25 Figure 2 is an end view;

Figure 3 is a section taken substantially on line 3—3 of Fig. 1;

Figure 4 is a back view of one of the end bars and associated parts;

30 Figure 5 is a section taken substantially on line 5—5 of Fig. 4;

Figure 6 is a view showing the stretcher disassembled with the parts positioned closely adjacent to each other so as to 35 occupy little space;

Figure 7 is a section taken substantially on line 7—7 of Fig. 6.

The stretcher includes a top bar 1 and bottom bar 2 each of which is provided in 40 its outer face with a longitudinally extending groove 3 and with securing pins 4 projecting from this groove for securing the edge portion of the curtain in the known manner. Bars 1 and 2 are each provided 45 at one end with a series of spaced openings 5 and at the other end with an opening 6. Openings 5 and 6 of top bar 1 are adapted for reception of supporting and adjusting pins 7 carried by side bars 8 adjacent to the upper ends thereof. Openings 5 and 6 of lower bar 2 are adapted 50 for reception of any one, selectively, of a series of supporting and adjusting pins 9 adjacent to the lower ends of the side bars. 55 Each side bar is also provided with a longitudinally extending groove 8^a from

which project securing pins 4^a similar to pins 4. By means of the pins 7 and 9 and the openings 5 and 6 in the top and bottom bars the effective width and length of the 60 rectangular frame formed by the side and end bars may be readily adjusted as desired.

For supporting the frame when set up I provide brace-bars 10 pivoted at their upper ends, at 11, to the outer face of the 65 respective side-bars 8. Each brace-bar 10 is provided in its inner face with a recess 12 adapted for reception of a rigid securing strip 13 pivotally secured at its lower end, at 14, in recess 12. At its other end 70 strip 13 is provided with a hook element 15 adapted for engagement over the shank of a headed pin 16 secured in side bar 8. The strip 13 co-acts with pin 16 to hold brace-bar 10 at an inclination to side bar 75 8, the two brace-bars thus acting to support the frame of the stretcher at an inclination, as in Fig. 2. To prevent any looseness of the stretcher frame when set up and supported by brace-bars 10 in the manner 80 described, top bar 1 and bottom bar 2 are each provided with a rearwardly projecting block 17, this block being provided adjacent to one end of the bar and fitting snugly against the inner lateral edge portion of the adjacent side-bar 8 (Fig. 3). This provides simple and efficient means for 85 holding the top and bottom bars at right angles to the side-bars and serves to effectively prevent all looseness or play between 90 the bars of the frames.

Each brace-bar 10 is provided, in its inner face, with a transversely extending slot 18 which is of substantially T-shape in cross-section. The neck portion of the slot receives 95 the shank of pin 16 and the head of the slot is adapted to receive head 16^a of the pin when the brace-bar is moved into parallelism with side-bar 8 as in Fig. 4. The pin 16 acts to hold the brace-bar in its folded 100 position adjacent to the side bar and prevents all looseness or play of the brace bar, strip 13 fitting snugly into recess 12 when the brace-bar and the side bar are folded together. When the frame is disassembled 105 the brace bars and side bars are folded together and the top and bottom bars are positioned closely adjacent to each other the end of one of these bars being in contact with the block 17 carried by the other bar, 110 as in Fig. 6. After this has been done the side bars 8 and brace bars 10 carried there-

by are placed adjacent to the top and bottom bars, the stretcher, when disassembled, being thus arranged so as to form a neat bundle which occupies but very little space.

5 The stretcher constructed in the manner illustrated and described may be readily produced at small cost and can be quickly and easily set up or taken down.

It may be found desirable in practice to 10 resort to changes in details of construction and arrangement of parts of the invention without departing from the field and scope of the same, and I intend to include all such variations, as fall within the scope of the 15 appended claim, in this application in which a preferred form only of my invention is disclosed.

What I claim is:

In a curtain stretcher, side bars provided 20 with spaced forwardly projecting pins, top

and bottom bars each provided in one end portion with openings adapted for reception of any of the pins, selectively, blocks secured on the inner face of each of the top and bottom bars adjacent to the other end thereof, said top and bottom bars being each provided with a pin receiving opening beyond said block and so related thereto that when a pin of the adjacent side bar is inserted through the opening the block is held in close contact with the adjacent edge of said side bar whereby said blocks coact with the side bar to brace the top and bottom bars and hold them at right angles to the side bar with which the blocks contact. 25 30 35

In testimony whereof I affix my signature.

HENRY H. KREIGER.
